The ornamental design for a eight sided fin-style LED corn-cob light bulb, as shown and described.

DESCRIPTION

FIG. 1 is a plan front view of a eight sided fin-style LED corncob light bulb showing my new design; the plan back view being a mirror image;

FIG. 2 is a right side view thereof; the left side view being a mirror image;

FIG. 3 is a bottom view thereof;

FIG. 4 is a top view thereof; and,

FIG. 5 is a perspective view thereof.

The broken lines in the drawings illustrate portions of an eight sided fin-style LED corncob light bulb which form no part of the claimed design.
